(Cl. D80—9)

To all whom it may concern:

Be it known that we, Alan C. Botsford, a citizen of the United States, residing at Brooklyn, in the county of Kings and State of New York, and Charles J. Chasse, a citizen of the United States, residing at Whitestone, in the county of Queens and State of New York, have invented a new, original, and ornamental Design for Portable Clothes Container, of which the following is a specification, reference being had to the accompanying drawings, forming a part thereof.

In the drawings:

We claim:

The ornamental design for a portable clothes container, substantially as shown.

ALAN C. BOTSFORD.
CHARLES J. CHASSE.
